UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

CIRCUIT ARRANGEMENT FOR MULTIPLEX COMMUNICATION.

Application filed February 24, 1923, Serial No. 620,398, and in Germany March 23, 1922.

Arrangements are known for multiplex telephony and telegraphy in which saturated iron core choke coils and a single generator are used in which the winding of the generator is divided in accordance with the number of the sending stages, or the saturated choke coils of the individual stages are connected in parallel with each other.

In accordance with the present invention, the choke coils are all connected in series. In this way the circuit arrangement is materially simplified because the same current is used for saturating all of them. The greatest advantage resulting from this arrangement is that harmonics produced by any one choke coil cannot reach the other sending circuits without passing through all the other coils and the generator. This eliminates many disturbances that arise in the use of parallel connections, wherein the harmonics generated by any one coil and its associated radio frequency circuit are directly applied to all the other sending circuits.

The single figure of the drawing is a diagrammatic representation of a circuit arrangement embodying the invention.

The illustrated circuit arrangement comprises a plurality of sending circuits A, B and C, each including a saturated iron core choke coil D. The choke coils D may be magnetized in any usual or suitable manner and are connected in series with an alternating current generator G. As shown, the sending circuits A, B and C are tuned respectively to wave lengths λ_1 , λ_2 , λ_3 , corresponding respectively to the fifth, seventh and ninth harmonics of the basic frequency of the generator. Any desired transmitting means as antenna circuits E, F, and G may be coupled to the sending circuits A, B and C.

Having described my invention, what I claim is:

1. A circuit arrangement for multiplex communication comprising, a plurality of sending systems, each including a saturated iron core choke coil, the choke coils being

connected in series with each other, and an alternating current generator connected in series with said choke coils.

2. A circuit arrangement for multiplex communication comprising, an alternating current generator, a plurality of iron core choke coils connected in series with each other and with the generator, and sending circuits connected selectively with the choke coils and tuned to different harmonies of the basic frequency of the generator.

3. In combination, a plurality of frequency changers, a source of alternating energy, said frequency changes and said source being coupled all in series with each other and a plurality of individual work circuits coupled to said frequency changers.

4. In combination, a plurality of static frequency changers, a source of alternating energy, said static frequency changers and said source being coupled all in series with each other and a plurality of individual work circuits coupled to said static frequency changers.

5. In combination, a plurality of frequency changers, a source of alternating energy, said frequency changers and said source being coupled all in series with each other and a plurality of individual work circuits tuned to different frequencies coupled to said frequency changers.

6. A circuit arrangement for multiplex communication, comprising a source of alternating current, a plurality of iron core static frequency changers coupled together in series with each other and with said source, and sending circuits coupled to said static frequency changers and tuned to different frequencies.

7. A circuit arrangement for multiplex communication, comprising a source of alternating current, a plurality of iron core frequency changers coupled together in series with each other, and with said source, and sending circuits coupled to said frequency changers and tuned to different frequencies.

ALEXANDER MEISSNER.
